UNITED STATES PATENT OFFICE.

GILBERT S. ELLITHORPE, OF CHICAGO, ILLINOIS, ASSIGNOR OF ONE-FOURTH TO
NORMAN D. FRASER, OF CHICAGO, ILLINOIS.

HEEL-LIFT.

1,303,869.

Specification of Letters Patent. Patented May 20, 1919.

Application filed October 24, 1918. Serial No. 259,547.

To all whom it may concern:

Be it known that I, GILBERT S. ELLITHORPE, a citizen of the United States of America, and a resident of Chicago, county of Cook, 5 and State of Illinois, have invented certain new and useful Improvements in Heel-Lifts, of which the following is a specification.

This invention relates to heel lifts of the general character set forth in my Letters 10 Patent of the United States No. 1,272,929 and No. 1,273,047, dated July 16, 1918, and is directed to a specific improvement having some of the characteristics of the invention set forth in said patent.

15 The main objects of this invention are to provide a resilient tread lift of an upwardly concave form best adapted to hug the heel tightly, especially about its edge, when secured by central fastening means, and which 20 may be thus applied in such manner as to fit smoothly and flat without any appreciable projections, hollows, ridges, or other irregularities. Further objects are to provide such a heel lift, the peripheral edges 25 of which are for the most part adapted to fit initially against the heel in applying the lift; to provide such a lift the front or breast part of which is so formed and adapted as to yield in such manner as to 30 avoid humps or ridges adjacent thereto or "kicking up" at the front corners as the lift flattens out in applying to the heel; and to provide a lift of this character in which the attaching means are well protected from 35 wear.

An illustrative embodiment of this invention is shown in the accompanying drawings, in which—

Figure 1 is a plan of the concave inner 40 side of a heel attachment or tread lift.

Fig. 2 is a longitudinal section on the line 2—2 of Fig. 1.

Fig. 3 is a front elevation or edge view 45 of the device as viewed from the right of Fig. 1.

Fig. 4 is a bottom plan view.

In the illustrative embodiment shown in the drawings, the lift 1 comprises a concavo-convex body 2 and a bradded fastener 3

secured to or embedded in the central part 50 thereof ready for attaching the lift to a heel, as by driving with a hammer or the like. Said body 2 is composed of resilient material adapted to be molded about the fastener 3, rubber or a compound thereof 55 being preferred.

The peculiar shape of the yielding body 2 is a matter of primary importance. Taken as a whole, it is concavo-convex with upwardly deflected edges. The central part 4 60 is flat and is surrounded by an upwardly turned border or marginal part 5, the outer edges being of substantially uniform height except on the front or breast side, where the outer edge is invertedly arched or bowed 65 below the plane of the side and back edges as shown at 6, thus obviating undue stress at this point, and permitting the adjacent lateral parts to yield backward and straighten out, when the lift is applied to 70 the heel. The flat central part 4 corresponds substantially in shape and extent with the plate-like body 7 of the fastener 3, which is preferably circular.

The fastener 3, it is to be understood, may 75 be substantially like that shown on the first sheet of drawings of my said Patent No. 1,273,047, and the inner face of the middle part 4 of the lift is apertured as at 10 to receive the corresponding brads 11 of another lift where a pair are nested together, as described in said patent.

Although but one specific embodiment of this invention has been herein shown and described, it will be understood that numerous details of the construction shown may be altered or omitted without departing from the spirit of this invention as defined by the following claims.

I claim:

1. A heel lift, comprising a resilient body 90 having a flat central part provided with a fastener embedded in and substantially co-extensive in area therewith, and a marginal outer part inclined upward around said central part on all sides, the edge of said outer part lying in a plane except in front where its edge is centrally bowed therebelow.

2. A heel lift, comprising a resilient body and a fastener of substantially circular shape embedded in the central part thereof, said body having a substantially circular flat central part co-extensive in area with said fastener, and a marginal outer part inclined upward around said central part on

all sides, the edge of said outer part lying in a plane except in front where its edge is centrally bowed therebelow. 10

Signed at Chicago this 16th day of Oct., 1918.

GILBERT S. ELLITHORPE.
